SCREEN ROLLER

Hughbert M. Lockhart, Highland Park, Mich.

Application July 21, 1947, Serial No. 762,319

2 Claims. (Cl. 160—313)

1

My invention relates to a new and useful improvement in a roller screen for windows and adapted for mounting in connection with a slideable window in such a manner that when the window is open, the screen will automatically be unrolled and cover or screen the open space.

It is an object of the present invention to provide a roller screen of this class which will be simple in structure, economical of manufacture, durable, compact, light, easily and quickly installed and highly efficient in use.

Another object of the invention is the provision of a roller screen of this class so constructed and arranged that when the window is closed, the screening member is entirely enclosed within a housing.

Another object of the invention is the provision in a roller screen of this class of a construction whereby the device may be easily and quickly mounted in position on a window and when mounted is prevented from undue disconnection from the attaching parts.

Another object of the invention is the provision in a roller screen of this class of a structure so arranged that the screening member will extend substantially from side to side of the window and be pressed at its edges against a stop so that a complete sealing of the window at the edges is thus provided.

Another object of the invention is the provision in a roller screen of this class of a supporting bracket for supporting the roller on which the screen is mounted so arranged and constructed that the screen itself at its opposite edges may project beyond the inner ends or faces of the supporting brackets.

Another object of the invention is the provision in a roller screen of this class of a structure so arranged that the screen may be prevented from unwinding after being removed from its mounting.

Other objects will appear hereinafter.

It is recognized that various modifications and changes may be made in the detail of structure illustrated without departing from the invention itself and it is intended that such shall be embraced within the scope of the claims which form a part hereof.

Forming a part of this specification are drawings in which,

Fig. 1 is an inside elevational view of the invention showing it applied with parts broken away,

Fig. 2 is a slightly enlarged sectional view taken on line 2—2 of Fig. 1,

Fig. 3 is a fragmentary, sectional view taken on line 3—3 of Fig. 2,

2

Fig. 4 is a slightly enlarged sectional view taken on line 4—4 of Fig. 2 with parts broken away and removed.

Fig. 5 is a sectional view taken on line 5—5 of Fig. 4,

Fig. 6 is a sectional view of the roller taken on line 6—6 of Fig. 4,

Fig. 7 is an enlarged sectional view taken on line 7—7 of Fig. 6,

Fig. 8 is an enlarged view taken on line 8—8 of Fig. 4,

Fig. 9 is a fragmentary, sectional view taken on line 9—9 of Fig. 1,

Fig. 10 is a fragmentary, sectional view taken on line 10—10 of Fig. 5.

The invention is adapted for use with a slideable window. In the drawings, I have shown a window sash 17 vertically slideable in the window frame 18 and provided with the lower rails 19. The window frame is also provided with a sill 20 against which the lower face of the rail 18 engages when the window is fully closed.

In the invention, I provide a housing embodying the top wall 21, the outer wall 27, the bottom wall 22, and the downwardly projected flange 23 extending downwardly from the top wall 21.

This downwardly projected flange 23 is provided at spaced apart points with the inwardly extending notches 24 adapted for the reception of fastening means 25, such as, nails or the like which are driven into the rail 19 of the window sash so that the housing will move in unison with the window sash.

At opposite ends of the housing, I provide supporting brackets which are U-shaped in formation and the legs 26 of which are secured by welding or in any other suitable manner to the inner faces of the top wall 21 and the bottom wall 22. The bight 28 of this U-shaped structure is inwardly off-set at its center to provide the U-shaped formation 29. In one of these U-shaped formations 29 is formed a slot 30, the purpose of which will appear hereinafter. In the other U-shaped formation is formed an opening 31 which is central thereof.

I provide a tubular roller 32 which is preferably formed from metal and into which is pressed as a press fit a disc 33 having a trunnion projecting outwardly from its outer face and adapted to project through the opening 31. This tubular roller 32 is cut away at one side, as at 35, so that the insertion of the trunnion 34 through the opening 31 may be effected and the roller positioned as shown in Fig. 4. It will be noted that the disc 33 is set inwardly from the end of the roller 32 and that the roller 32 terminates with

50

its end substantially in engagement with the inner face of the bight 28 of the supporting bracket.

Pressed inwardly of the roller 32 at the opposite end by a press fit or suitably secured thereto by welding or any other desired manner, is a cup-shaped support 36 projecting centrally through which is a rod 37 embraced by a coil spring 38. One end of this coil spring 38 is angularly turned and directed through the lug 39 formed on the face of the cup-shaped member 36. The inner end of the rod 37 is split to provide the space 40 for reception of the angularly turned end 41 of the spring 38. The outer end of the rod 37 is flattened at both sides to provide a flat faced structure and this flat face structure is adapted to engage in the slot 30 formed in the inwardly pressed U-shaped formation 29 so as to prevent rotation of the rod 37 relatively to the bracket. Formed through this flat portion inwardly of the bracket is an opening 43, the purpose of which will be explained later, and which is in alignment with an opening 44 formed through the tube 32.

Glued or otherwise suitably secured to the periphery of the tube 32 is one end of a screen 46, the opposite end of which is reenforced by the reinforcing plates 47 and 48 which carry the angularly turned portions 48a and 47a, the screen being clamped at its edges along the free end between these plates. A portion of the plate 47 is turned outwardly to provide a gripping portion 49 and this outwardly turned portion extends angularly to the plane of the main body of the plate 47 and is slightly curved at the point where it is turned outwardly, this outwardly portion, in addition to serving as a hand grip, is provided with notches 50 which are adapted to engage under an eyelet of a screw 51 which is screwed into the sill 20 and projects vertically upwardly therefrom.

In use, the spring is mounted in the lower end in the manner indicated with all of its associated parts which have been described. By rotating the rod 37 in one direction, the spring 38 may then be wound and when wound in this condition a pin 45 may be projected through the opening 44 and into the opening 43 so as to lock the rod 37 against reverse rotation, this pin being extended through, if necessary, a layer of the screening which is wound upon the roller. The screen, of course, will be in unwound position when the spring is placed under tension. The roller may then be mounted in the housing in the manner indicated and the pin 45 removed which will permit the roller 32 to rotate so as to wind the screen onto the roller 32. Any unwinding of the screen from the roller 32 will again, of course, place the spring 38 under tension and the initial tensioning of the spring 38 is such that when the screen is finally wound upon the roller 32, there will be a certain amount of tension in the spring 38. When the roller 32 rotates freely to wind the screen 46 thereon, the outwardly projecting portions 49 will engage against the edge of the downwardly projecting portion 23 and prevent the edge reenforcement plate on the end of the screen from entering the housing but the remaining portion of the screen will be entirely enclosed within the housing and also a portion of the reinforcing plates 47 and 48 so that when the screen is wound upon the roller 32, it will be sufficiently enclosed within the housing as to protect it from the elements, such as, snow, sleet, rain, etc. The housing is then mounted in position, as shown in Fig. 1. It will be noted that the ends of the housing are cut away, as at 58, this cutaway

portion providing the necessary space for the stop 54, the housing lighting in the space 52 between the outer stops 53 and 54. The housing is then moved downwardly so that the notches 24 will engage over the nails 25 which project outwardly from the outer face of the sash rail 19, thus mounting the housing detachably on the rail 19. The window is then raised slightly and the screen 46 pulled downwardly. The lower edge of the screen then is tilted so that the curved or angularly extended portion 49 will extend parallel to the upper face of the sill 20 whereupon the lower edge of the screen may be moved inwardly of the sill 20 to engage the eyehooks 51 in the notches or slots 50. The tilting or twisting action is then released and the parts move into the position shown in Fig. 9, thus securely fastening the lower edge of the screen to the sill 20. When the window is closed, the screen will wind into the housing and when it is open, it will move into open position. This screen lies between the stops 53 and 54 and is pressed at its edges against the outer face of the stop 54 by means of the rubber roller 56 which is mounted on the shaft 57 journaled in the bead 55 formed on the edge of the bottom 22. It will be noted that the housing 21 extends substantially from side to side of the window and, thus, the screen also extends substantially from side to side of the opening in the window frame and being pressed at its edges against the face of the stop 54 there is no crack or crevasse through which flies or the like may be permitted to pass. Another feature of the screen is that any outward thrust delivered to the screen will be taken up by a further unwinding of the roller inasmuch as the screen may move from the outer face of the stop 54 to the inner face of the stop 53. By having the connection at the window sill in the manner described, outward thrust delivered to the screen will not disengage the connection at the window sill as it is necessary that the lower edge of the screen be rocked in order to release the eyelet screws 51 from the notches 50 in which they engage.

Experience has shown that a screen constructed in this manner is one which is most efficient in use and may be left attached to the window even during the winter so that it will serve as a screen against dust when the window is open and in the wintertime for ventilation.

In order to remove the construction from the window, it will be necessary to grasp the lower edge of the screen and rock it until the eyelet screws 51 may be disengaged from their notches 50 whereupon the screen may roll into the housing. The housing may then be lifted upwardly to disengage the screws or bolts 25 from the notches 24. When the screen is attached to the window sill, the tension of the screen, of course, keeps the housing pressed downwardly so that upward movement of the housing relatively to the fastening means 25 is prevented.

What I claim as new is:

1. In a roller screen of the class described, a tubular roller adapted for having a screen wound thereon; a disc mounted in one end of said roller and positioned inwardly from the end thereof; a trunnion attached to and projecting outwardly from said disc and terminating flush with the end of said roller, said roller at the location of said trunnion being cut away at one side; a cup-shaped member mounted in the opposite end of said roller and positioned inwardly from the end thereof; a rod rotatably projected through said cup-shaped member; a spring embracing said

rod, one end of said spring being attached to one end of said rod and the opposite end of said spring being attached to said cup-shaped member, said cup-shaped member being in fixed relation to said tubular roller, and said rod projecting outwardly from said cup-shaped member and terminating with its end flush with the end of said roller.

2. In a roller screen of the class described, a tubular roller; a screen wound on said roller; a disc mounted in one end of said roller and positioned inwardly from the end thereof; a trunnion attached to and projecting outwardly from said disc and terminating flush with the end of said roller, said roller at the location of said trunnion being cut away at one side; a cup-shaped member mounted in the opposite end of said roller and positioned inwardly from the end thereof; a rod rotatably projected through said cup-shaped member; a spring embracing said rod, one end of said spring being attached to one end of said rod and the opposite end of said spring being attached to said cup-shaped member, said cup-shaped member being in fixed relation to said tubular roller; said rod and a support 23

at one end of said roller projecting inwardly thereof for engaging the outer end of said rod for supporting said end of said roller; and a support projecting inwardly of the opposite end of said roller and engaging said trunnion for supporting the adjacent end of said roller.
